(57) **CLAIM**

The ornamental design for a basketball possession indicator, as shown and described.

DESCRIPTION

FIG. 1 is a perspective view of a basketball possession indicator showing our new design;

FIG. 2 is a front elevational view thereof;

FIG. 3 is a top view thereof;

FIG. 4 is a rear elevational view thereof;

FIG. 5 is a bottom view thereof;

FIG. 6 is a right side elevational view thereof; and,

FIG. 7 is a left side elevational view thereof.

Stippling in FIGS. 1-4, 6 and 7 shows portions of the basketball possession indicator having a frosted appearance.
